UNITED STATES PATENT OFFICE.

JOHN W. CONKLIN, HENRY L. SIDMAN, AND EUGENE WHRITNER, OF RAMAPO, NEW YORK.

FILE-CUTTING MACHINERY.

Specification of Letters Patent No. 9,194, dated August 17, 1852.

To all whom it may concern:

Be it known that we, JOHN W. CONKLIN, HENRY L. SIDMAN, and EUGENE WHRITNER, of Ramapo, in the county of Rockland and 5 State of New York, have invented certain new and useful Improvements in Machinery for Cutting Files; and we do hereby declare the following to be a full, clear, and exact 10 description of the construction and operation thereof, reference being had to the annexed drawing, and letters of reference marked thereon, forming part of this specification, in which—

Figure 1 is a side elevation of the machine, a portion of the frame being removed 15 to expose the cutting apparatus. Fig. 2 is a central longitudinal section. Fig. 3 is a transverse section, taken as denoted by the red line 2 2 of Fig. 2 and looking toward the 20 cutting apparatus. Fig. 4 is an elevation of the rear end, and Fig. 5 is a top view of the file bed or carriage.

The peculiarities of our file cutting machinery have relation to a combination for 25 the automatic graduation of the blow at the tip of the blank, or commencement of the operation.

In the annexed drawing A is a bench, having at top guide ways a^1 a^1 for the file bed 30 or carriage B, to slide to and fro upon. One of these ways is provided with a bead b fitting into a groove in the carriage for the further steadiment and more exact guidance of the carriage. Mounted on this bench A, 35 are two standard frames c , c , which afford support and journal bearing to the hammer, cutter, cams, etc.

The top of the carriage B, is provided 40 with the following described device for holding the blank: United at their front ends by a cross piece d are two long thin strips of metal c , having each a pair of longitudinal grooves or slits e , e and also a pair of oblique ones f , as represented in Fig. 5. 45 The longitudinal grooves slip over pins e' e' in the carriage top. These pins are screw threaded and provided with thumb nuts. g are clips or slides having small flanges on their inner ends for clamping the file blank. 50 From these clips or slides g project upward pins f^1 , which occupy the oblique grooves f . It will readily be perceived that on drawing the plates or strips C , forward, the pressure of the rear side of the oblique grooves f 55 upon the pins f^1 will cause the clips or slides to approach the blank and hold it fast,

and with a reverse motion of the strips c , to recede again and allow another blank to be inserted. The clips or slides being arranged upon the file bed on either side of the 60 file, are brought to their desired places when the blank is to be clamped, and held fast by means of the thumb nuts on the pins e' e' . The tang of the file blank is inserted within a staple h of the bed admitting vertical but 65 preventing lateral motion. Vertical motion has to be provided on account of the swelling form usually given to files, which occasions the ends to rise from the bed in proportion to the distance of the part operated on. 70

The cutter D, does not differ materially in form from the ordinary file chisel, that is, it has a flat taper toward the cutting edge or blade and a pyramidal taper toward the 75 heel. It is placed within a socket i , said socket nearly fitting it at top, but flaring toward the lower portion, so as to admit an encircling cushion w of caoutchouc or india rubber to the cutter shank, having for its 80 object the rendering the face or edge of the cutter self-adaptable to the face of the file blank, and thus effectually preventing any recoil of the cutter, and the consequent formation of false or imperfect grooves. 85 The cutter is preserved from falling out of the socket i by a pin i' passing through the head of said socket and shank of the cutter. The socket itself is cylindric and can be set in its gate or cross head j , so as to present 90 the edge of the chisel at any angle desired with reference to line of motion. This done the socket is secured to said gate by set screw j' . The ends of the gate or cross head j work in grooves k k on the frame c , which 95 admits of a slight upward motion parallel with the axis of the cutter. This upward motion is given by means of levers E, E, the ends whereof are inserted in eyes l on the gate. These levers have their fulcra upon a cross rail m attached to the frames c . This rail also affords support to the fulcrum n of the hammer F, in the manner shown. The heels of both the hammer helvæ G and the levers E, are depressed at regular intervals 100 by the rotating cam H, mounted on a horizontal propelling shaft I, said cam H, being so formed as to lift both hammer F, and cutter D, nearly simultaneously, and to drop the latter first, which thus has opportunity 105 to adapt itself to the face of the blank, and also to hold the latter firmly down upon the 110

carriage, and thus dispense with the need of a roller to hold the blank to its work. On these accounts it is decidedly preferable to have the cutter as in this machine detached 5 from the handle. The hammer head being adjusted in its helve G so it will strike the chisel or cutter precisely central, can be held fast to its proper place by means of the set screws σ σ passing through said hammer 10 head and entering a recess p in the helve. The force of the hammer derivable from its weight is still further augmented by spiral springs q q , whose stress, which is at its minimum at the commencement of the cutting 15 on the narrow tip of the file, is made to increase so as to augment the force of the cut as the surface of the blank broadens by the following arrangement of mechanism: Affixed to the sides of the carriage are racks 20 r r , in which gear pinions s s of a horizontal transverse shaft J journaling in the frame. On this shaft J , and on the outsides of the pinions s s are placed cams or eccentrics K , K , and interposed between these cams K 25 and pinions s are rods L . These rods L , are bifurcated where they pass the cams, so as to straddle the pinion shaft J , and carry at their lower extremities rollers M , which bear up against the faces of the cams K , by the 30 stress of the springs q before mentioned, which surround the upper portions of rods L , and which at their lower ends bear against a cross piece N , attached to the hammer helve G , and at their upper ends bear 35 against nuts t on the upper ends of the rods. On inspection of this mechanism it will be seen that as the carriage advances the slow rotation of the pinions s will gradually bring a larger part of the cams K in contact 40 with the rollers M , and by this means drawing them and their attached rods downward must contact the springs q and thus increase the stress upon the hammer. The intermittent advance of the carriage between every

two successive strokes of the hammer is ac- 45 complished by means of a horizontal screw O , journaling within the bench, and which, when desired to be effective is made so by bringing down a semi-circular nut P , upon it by means of the handle Q , having its 50 fulcrum Q' in the file bed or carriage and attached to the nut P , by an arm R see Fig. 4. This screw is rotated by a pawl S , and ratchet wheel T worked by a cam U , on the same shaft containing that which operates 55 the hammer and cutter, and coming into play at the same time, and ceasing to act before the chisel descends, serves to move the bed or carriage before the hammer and cutter are liberated from the cam H . V is 60 a rack attached to the side of the bed and having one or more pawls W , prevents the recession of the carriage beneath the strokes of the hammer. When the operation of cutting the file on one side is finished, the carriage is detached from the screw and run back and the file blank turned over and clamped. 65

Having described our improvements in machinery for cutting files, what we claim 70 as our invention and desire to have secured to us by Letters Patent, is—

As herein constructed and combined, the racks r , pinions s , cams or eccentrics K , rods L , and springs q , in connection with the 75 vibrating hammer F , as described for the graduation of the blow at the commencement of the operation.

In testimony whereof we have hereunto signed our names before two subscribing 80 witnesses.

JOHN W. CONKLIN.
HENRY L. SIDMAN.
EUGENE WHRITNER.
